UNITED STATES PATENT OFFICE.

MARTIN J. NELSON, OF CHICAGO, ILLINOIS, ASSIGNOR OF ONE-HALF TO GUSTAF A. LARSON, OF BERWYN, ILLINOIS.

DRYING APPARATUS.

Application filed March 12, 1925. Serial No. 14,900.

My invention has reference more particularly to a device for drying clothes and the like, wherein a current of heated air is passed through a rotating drum or tumbler 5 containing the clothes.

The principal objects of my invention are to insure a more thorough and uniform drying of clothes and the like; to facilitate the heating of the air for use in the drying operation; to supply the heated air to the tumbler in such a manner that the current of drying air extends from end to end of the tumbler; to afford a convenient means for holding the tumbler inoperative when it is 10 opened up; and in general to simplify, improve and increase the efficiency of drying apparatus of this character.

The invention consists in the novel arrangements, constructions and devices to be 20 hereinafter described and claimed for carrying out the above-stated objects and such other objects as will appear from the following description of a certain preferred embodiment illustrated in the accompanying 25 drawings, wherein—

Fig. 1 is a vertical, transverse sectional view, taken through the drying apparatus;

Fig. 2 is a longitudinal sectional view, taken substantially on the line 2—2 of Fig. 30 1, with certain parts in elevation;

Fig. 3 is a fragmentary perspective view of the heater;

Fig. 4 is a detail view of portions of the tumbler and casing and shows in section the 35 locking device for holding the tumbler against movement, said device being in the released position; and

Fig. 5 is a similar view of the locking device in the locking position.

Like characters of reference designate like 40 parts in the several views.

Referring to the drawings, the reference numeral 1 indicates a base with an upstanding frame or casing 2, which is formed at an 45 elevated point with a substantially cylindrical housing 3, in which a correspondingly formed drum or tumbler 4 is journaled to rotate. The respective end walls 5 of the drum or tumbler, which are preferably solid 50 panels, have aligned stub shafts 6 and 7 secured thereto and projecting outwardly therefrom and journaled respectively in the bearings 8 and 9 with which the end walls 2 of the housing are provided.

55 The shaft 7 extends beyond the bearing 9

into a case 10, which contains any conventional form of reverse gearing actuated by the pulley 11 to rotate the drum or tumbler 4 alternately in opposite directions.

The drum or tumbler 4 is designed to contain the clothes which are dried by circulating heated air therethrough, and it is formed with a circumferential wall of screen wire sections 12 with inwardly extending longitudinal ribs 13 therebetween, which serve in the rotation of the drum or tumbler 4 to agitate the clothes and permit the currents of air, which pass through the screen sections 12, to circulate thoroughly through the entire mass of clothes.

In order to afford access to the drum or tumbler 4 for filling and emptying same, one of the screen sections, indicated at 14, is hinged at 15—16 to one of the rib members 13 and provided at the free edge with 70 one or more releasable latches 17 which interlock with the other adjoining member 13 or a portion of the circumferential wall of the drum 4 so as to hold the door or hinged section 14 in the closed position.

The housing 3 is provided at one side with an opening through which the door or hinged section 14 of the tumbler may be swung to the open position shown in dotted lines at 14^a in Fig. 1, and this opening is 75 normally closed by a door 18, which is hinged at its upper edge to the housing 4 as indicated at 19 so as to swing to the open position shown in dotted lines at 18^a in Fig. 1, or to close the opening in the side of the 80 housing 3 as shown in full lines in said figure, and said door may be held in the closed position by any convenient form of latch 20.

It is desirable when filling and emptying the drum or tumbler 4 or working with the 85 clothes therein, that the drum or tumbler should be held against turning movement, and in order to accomplish this automatically and insure locating the drum, when stationary, in the proper position so that the 90 drum opening registers with the opening in the housing 3, a locking member 21 is arranged for operation by the hinge 16 so that when the cover or door 14 is opened, said member is projected into an opening or 95 socket 22, preferably reinforced, in the adjoining end wall of the housing 3. This member 21 is bored out and keyed at 30 on the end of a shaft 23, which serves as a pin- 100 tle for the hinges 15 and 16, said shaft being 105 110

held against turning in any convenient manner, as by pinning the end thereof adjacent to the hinge 15 as at 24 in a socket 25, which is formed in the end wall of the drum 4 or in 5 the end of the adjoining rib 13. The inner end of the member 21 is formed with a diagonal face and the movable leaf of the hinge 16 has a sleeve section 26 movable therewith on the shaft 23 and formed with a 10 corresponding diagonal outer end face which is arranged so that when the cover or door 14 is closed, said diagonal faces fit together and permit the member 21 to be withdrawn free of the opening 22. The outer end of the 15 member 21 is slidably engaged in an aperture of a bracket 27 which is secured to the end of the drum 4 and a tension spring 28, encircling the member 21 and interposed between the bracket and an annular rib 29 on 20 the rear end of the member, resiliently holds the locking member 21 in the retracted position. When the door 14 is opened and the hinge 16 accordingly operated, the sleeve section 26 is rotated on the shaft 23 and the 25 diagonal end face thereof acts as a cam against the diagonal inner end face of the locking member 21 and forces the latter outwardly against the tension of the spring 28. Obviously the member 21 cannot move outwardly sufficiently to permit opening of the 30 door 14, unless the member 21 is in axial alignment with the opening or socket 22, into which it is adapted to be projected, and in this position the drum is in the proper 35 relative position with respect to the housing so that the door 14 may be swung outwardly through the corresponding opening in the wall of the housing 3.

Mounted on the frame 2 above the housing 3 is a heater casing 31, which is closed at the opposite ends by removable panels 32, the panels being held in place by screws or other suitable fasteners 33 which engage the 40 upright flanges of angle irons 34 and 35 secured onto the walls of the heater casing. The angle irons 35 extend across the end walls of the heater casing 31 at a considerable distance below the top wall thereof and serve to support a heater which is indicated 45 as a whole at 36 and includes a plurality of shells 37 of substantially the same length as the heater casing, the opposite ends of said shells resting on the respective inturned flanges of the angle irons 35. Each of said 50 shells is triangular in cross-section and comprises a bottom portion 37^a and inclined side portions 37^b. Laterally spaced burner pipes 38 extend through the respective shells 37 and are connected with a feed pipe 39, said 55 burner pipes having jet apertures at intervals therealong. The triangular-shaped shells 37 are spaced apart somewhat so as to provide, therebetween at the outer sides thereof, slots or openings 40 to admit air at 60 both sides of each of the shells 37. Parti-

tions 41, 42, 43 and 44 are arranged at a short distance from and substantially parallel with the opposite side walls of the shells 37, so that the air entering through the openings 40 is required to pass upwardly 70 along and in close contact with the walls of the shells 37 and is thus heated by the burners 38. The respective passageways between the shells 37 and partitions 41, 42, 43 and 44 lead into a common space within and 75 at the top of the heater casing 31 and from here it is exhausted through the passageway 45 into the top of the housing 3.

For enforcing circulation of air through the heating device and the tumbler, an exhaust fan 46 is mounted on the base 1 below the housing 3 and a large outlet, at the bottom of the housing 3 and substantially midway between the ends of the housing, is connected by the duct 47 to the exhaust fan 80 intake. This fan may be operated in any convenient manner, a pulley 48 being shown in the present case, whereby a belt connection may be made from any convenient 85 source of power.

One side wall of the heater casing 31 below the heater 36, is provided with a large opening, which may be closed by a screen 49 if desired, to admit air to the under side 90 of the heating device for passage through the heating channels, and it will be understood that when the exhaust fan 46 is in operation and clothes have been placed in the tumbler 4 and the latter is rotated back and forth, the exhaust fan will draw air in through the screened opening 49, past the side walls of the heater shells 37, where the air will be heated to the proper temperature to effect satisfactory drying, and after being heated, the air is directed downwardly 95 through the passageway 45 through the tumbler 4 and the clothes therein and then exhausted through the fan 46.

The partitions 41, 42, 43 and 44 may be supported in proper relation to the shells 110 37 in any desired manner, for example, by a plurality of angle clips 50 fastened to the panels 32. Air is admitted to the burner chambers in the respective shells 37 for combustion purposes through openings 51, which 115 are provided in the removable panels 32 and suitably located so as to register with the bottom portions of the ends of the heater shells 37, said openings, however, being terminated somewhat below the upper extremities of the triangular-shaped shells 37 whereby the air heated in the shells 37 is to a considerable extent trapped in the upper portions thereof thus maintaining the sides 120 of the heater shells at an efficient temperature. The side walls of each of the shells 37 are provided near their upper extremities with a series of small vent openings 52 (see Fig. 3).

The passageway 45, through which the 130

heated air enters the tumbler housing, extends from end to end of the housing so that the blast of air entering the housing 3 extends the full length of the tumbler 4 and thus serves to subject the clothes in 5 all parts of the tumbler uniformly to the drying operation. The partition 41 which forms a side wall of the passageway 45, is convergently arranged with reference to the 10 wall 52^a which forms the other side wall of the passageway 45 and gives to said passageway, in transverse section, somewhat of a nozzle shape to concentrate the air and cause it to enter the housing somewhat in 15 the form of a blast. The partition 41, which forms a permanent part of the heater casing, serves as an outer wall of the air space at the side of the innermost heater shell 37, and is maintained by reason of its proximity 20 to the heating elements, in a heated condition, and thereby heats the passageway 45 through which the air enters the tumbler. It will be noted that all air entering the drying chamber is first heated by reason of 25 the location of the passageways at the sides of the heater shells and through which the air must first pass. It will be noted that the area of the opening in the housing which is normally closed by the door 18 is much 30 greater than the area of the opening which is covered by the screen 49, which arrangement in conjunction with the location of the passageway 45 provides for automatic control of the air currents through the drying 35 chamber when the door 18 is opened. Upon opening the door 18 the suction of the fan is satisfied by cold air drawn in through the closer and larger opening and the circulation of the heated air practically ceases. 40 The heated air is, therefore, under control, there being no opportunity for it to rush out into the face of the operator.

While I have shown and described my invention in a preferred form, I am aware 45 that various changes and modifications may be made without departing from the principles of my invention, the scope of which is to be determined by the appended claims.

I claim:

50 1. In a drying apparatus of the class described, the combination of a casing having an inlet at the top extending from end to end thereof and an outlet at the bottom, an exhaust fan connected with the outlet for withdrawing air from the interior of the casing, a heater casing superposed on and extending from end to end of the first mentioned casing and extending over the aforesaid inlet opening, heating means in the 55 heater casing having a plurality of air heating passageways opening into a common chamber at the top of the heater casing and an upright partition in the heater casing interposed between the heating means and said inlet of the first mentioned casing and ter-

minating below the top wall of the heater casing, and a drum journaled in the first mentioned casing and extending lengthwise of the inlet opening and having screen-like circumferential walls.

70 2. In a drying apparatus of the class described, the combination of a casing, a drum journaled to rotate in said casing and having screen-like walls, a heating device comprising a plurality of laterally spaced elongated burners in individual elongated compartments of triangular-shaped cross section, said compartments being interposed between and separated from convergent air passageways, and means adapted to draw 80 air upwardly through said passageways and downwardly through the drum in the casing.

75 3. In a drying apparatus of the class described, the combination of a casing having 85 a drum with reticulated circumferential walls journaled to rotate therein, a heater casing mounted on and extending from end to end of the first mentioned casing and having oppositely inclined pairs of substantially parallel partitions forming elongated chambers of triangular-shaped cross section having a separate air space, open at the top and bottom, extending upwardly at both sides of each chamber, a common duct leading 90 from said air spaces into the first mentioned casing, a burner pipe extending lengthwise in each triangular-shaped casing, and a blower for circulating air through the air spaces of the heater and through the 95 drum in the first mentioned casing.

4. In a drying apparatus of the class described, the combination of a casing having an opening, a door for closing said opening, a container journaled to rotate in the casing 105 and having a corresponding opening provided with a door, means operated by the opening of the latter door to lock the container against rotation, an air heater, and a blower for circulating air from the heater 110 through the drum in the casing.

5. In a drying apparatus of the class described, the combination of a casing, a drum journaled to rotate in the casing and having a hinged door affording access to the 115 drum, a locking member on the drum adapted to be projected outwardly therefrom by the opening movement of the door, and a socket in the casing adapted to be engaged by the locking member.

120 6. In a drying apparatus of the class described, the combination of a casing, a drum journaled to rotate in the casing, a door hinged on the drum and affording access thereto, a locking member adjacent the door hinge, a cam member movable with the door for operating the locking member, and a socket in the casing with which the locking member engages, when the door is opened, for holding the drum against rotation.

7. In a drying apparatus of the class described, the combination of a casing having an opening and a door for closing same, a drum journaled to rotate in the casing and 5 having an opening with a door for closing same, said latter door being adapted to swing through the opening in the casing

to the open position, and interengaging means on the casing and drum and operable by the drum door to interlock the drum and 10 casing when the drum opening is at the opening in the casing.

MARTIN J. NELSON.
